UNITED STATES PATENT OFFICE.

ERNEST MAASS, OF WASHINGTON, DISTRICT OF COLUMBIA.

DESIGN FOR A CLOSET-SEAT PAD.

SPECIFICATION forming part of Design No. 35,273, dated November 5, 1901.

Application filed November 3, 1900. Serial No. 35,426. Term of patent 7 years.

To all whom it may concern:

Be it known that I, ERNEST MAASS, a subject of the German Emperor, (but having made declaration of citizenship of the United States,) residing at Washington, in the District of Columbia, have invented and produced a new and original Design for Closet-Seat Pads; and I do hereby declare the following to be a full, clear, and exact description 5 of the same, reference being had to the accompanying drawings, forming a part thereof.

Figure 1 is a plan view of a closet-seat pad, showing my new design; and Fig. 2 is a top elevation thereof.

15 The leading or material feature of my design consists in the particular shape of closet-seat pads, as shown in the drawings and now described.

A block or pad of numerous sheets has a 20 straight base 5, with converging side edges 4 and a double compound curve 6 at its top edge,

forming a central cavity in the pad. A similar-shaped backing 3 is mounted on the rear of the pad and has its contour in register with that of the pad. The pad further has projecting tabs or flaps 7 at its top corners and rows of perforations 8 along the side edges 4, which edges are faced with longitudinal securing-strips 9 in alignment with the rows of perforations 8. 25

Having described my invention, what I claim as new, and desire to secure by Letters Patent, is—

The design for a closet-seat pad, as herein shown and described. 30

In testimony whereof I affix my signature in presence of two witnesses. 35

ERNEST MAASS.
